UNITED STATES PATENT OFFICE.

WILHELM KÖHLER, OF FÜRTH, GERMANY.

SPRING MECHANISM FOR TIMEPIECES.

SPECIFICATION forming part of Letters Patent No. 668,191, dated February 19, 1901.

Application filed June 5, 1900. Serial No. 19,105. (No model.)

To all whom it may concern:

Be it known that I, WILHELM KÖHLER, jeweler and watchmaker, a subject of the Emperor of Germany, and a resident of Fürth, 5 Bavaria, in the Empire of Germany, (and whose post-office address is No. 16 Sternstrasse, Fürth, Bavaria,) have invented a certain new and useful Clock-Winding Mechanism, of which the following is an exact, full, 10 and clear description.

This invention relates to a spring driving mechanism with two driving-springs for clocks and watches, according to which by turning a key to the right and left the winding of both spring-barrels is rendered possible.

According to known similar arrangements three or four plates are necessary for mounting or journaling the spindles of the spring-barrels, whereas the present construction only 20 requires two plates.

Referring to the accompanying drawings, Figure 1 is a central longitudinal section through the spring-barrels; Fig. 2, a section on the line A B of Fig. 1, as seen on the right. 25 Figs. 3 and 4 are, respectively, elevations of the attachments at the ends of the spindle.

The spring-barrels are arranged between plates *a* *b*. At the center of barrel *c* a spindle or a core *d* is arranged, which extends 30 through the plate *a* and, with its cylindrical extension *e*, of less diameter, also through the plate *b*. On the end of the spindle *d*, passing through the plate *a*, is keyed the ratchet-wheel *f*, with which engages a pawl *g*, pivoted 35 to the plate *a*. The second spring-barrel *h* is provided with a hollow core or a hollow arbor *i*, which is loosely mounted on the extension *e* of the spindle *d* and passes through the plate *b*. The motion of the spring-barrel *h* and its 40 arbor *i* in only one direction is secured or insured by a ratchet-wheel *k*, fixed to the latter, a pawl *l* engaging with such wheel.

The winding of the spring-barrels is effected by two ratchet-wheels *m* and *n*, of which the former is securely or firmly fixed 45 to the part *e* of the spindle *d* in a suitable manner, while the wheel *n* is secured on that part of the hollow spindle *i* which extends beyond the plate *b*. With these ratchet-wheels *m* and *n*, which are provided with oppositely-directed teeth, engage two pawls *o* *p*, which are pivoted to a disk *q* and operated upon by a spring or springs *r*. The disk *q*, with its hub *s*, is securely fixed to the end of the spindle *d* and can be turned in the one or other 55 direction by the handle-piece *t*. On account of this rotation of the handle-piece in alternate directions either the ratchet mechanism *o* *m* is actuated, which effects the tension of the spring of the barrel *c*, or the ratchet-gear *p* *n* is operated, which actuates the hollow spindle *i* of the spring-barrel *h* for tensioning 60 the spring of same. The function of the ratchet *f* and its pawl *g* is to prevent the reverse rotation of the spindles *d* *e* and unwind- 65 ing of the springs.

Having now particularly described and ascertained the nature of the said invention, I declare that what I claim, and wish to secure by Letters Patent, is—

In a clock-winding mechanism, the combination with a solid winding-arbor *d* carrying the spring-barrel *c*, the ratchet-wheel *f* and the ratchet-wheel *m*, of a hollow spindle *i* carrying the spring-barrel *h* and the ratchet-wheels *k* and *n*, said spindle being mounted 75 on one end of said solid arbor, substantially as set forth.

In witness whereof I have hereunto set my hand in presence of two witnesses.

WILHELM KÖHLER.

Witnesses:

HEINRICH HUBER,
OSCAR BOCK.
